SILENCER

Robert L. Hoyle, Lombard, Ill., assignor to Burgess Battery Company, Chicago, Ill., a corporation of Wisconsin

Application September 1, 1938, Serial No. 227,951

7 Claims. (Cl. 181—53)

The present invention relates to silencers and particularly to silencers for quieting the exhausts and intakes of internal combustion engines.

It is the object of the invention to provide an improved silencer which possesses high silencing effectiveness and offers little restriction to the flow of gases therethrough, and which is of simple and economical construction.

The silencer of this invention is related to the combined silencer and spark arrester of my co-pending application Serial No. 197,193, filed March 21, 1938, and also to the silencer disclosed and claimed in the co-pending application of my co-worker Willis L. Manning, Serial No. 216,856, filed July 1, 1938. Briefly, it relates to a silencer of the retroverted passage type in which conduits are provided for the inlet and outlet passages but none are provided for the intermediate passage between these two, the sounds and gases being free to employ the entire space within the silencer chamber for this passage. Such construction is simple and yet highly effective for the silencing function, and it has an advantage peculiar to itself of not requiring a tail pipe of appreciable length to be connected to the outlet. In the more recent silencers which do not employ baffles to accomplish the silencing function, it has been found necessary to employ a tail pipe of appreciable length to obtain what is called a loading effect upon the silencer. Besides representing an expense, such a tail pipe, in many applications because of space requirements, is inconvenient or impracticable. In such situations the present type of silencer is of particular value.

In the said co-pending Manning application, a silencer is disclosed in which the inlet and outlet conduits are perforated. I have discovered that it is not necessary that both of them be perforated, but that one of them may be imperforate, or solid walled. The silencing effectiveness is not impaired by the use of a solid walled tube at one end of the chamber, and it represents a simplification and economy in construction. Such construction also facilitates the adjustment of the frequency response of the silencer, that is, the sound frequencies for which it is effective. This may be varied to some extent by varying the proportion of the conduit walls occupied by the perforations thereof, and where the conduits extending from one end of the silencer only are perforated the control of the frequency response is simplified. The manufacturing operations are simplified also, since the use of solid conduits avoids the perforating operation.

In the drawing:

Fig. 1 is a longitudinal sectional view of one form of the silencer of this invention;

Fig. 2 is a transverse sectional view along line 2—2 of Fig. 1;

Figs. 3 and 4 and 5 are longitudinal sectional views of modifications of the silencer of this invention; and

Fig. 6 is a transverse sectional view along line 6—6 of Fig. 5.

The silencer of Figs. 1 and 2 comprises an imperforate casing 10, closed at its ends by end walls 11 and 12. Said end walls have inlet opening 13 and outlet opening 14 therein respectively, said openings being displaced laterally with respect to each other and to the center line of the silencer. 15 Perforated, open-ended inlet tube 15 is mounted in inlet opening 13 and extends into the chamber toward the opposite end wall 12, the inner end stopping in spaced relation to said end wall 12. Solid walled, open-ended outlet tube 16 is 20 mounted in outlet opening 14 and extends into the chamber toward the opposite end wall 11, the interior end thereof being spaced from the inlet end wall 11 in the same manner as the end of inlet tube 15 is spaced from outlet end wall 12. 25 The two tubes are arranged in juxtaposed relation within the chamber and extend laterally adjacent each other throughout a large proportion of their length. The perforations or openings in the tube 15 in this form of the invention, as well as the perforations or openings in the perforated tubes of the modifications which will be described hereinafter, may be other than round and may be larger or smaller than shown.

In operating the silencer for silencing the exhaust of an internal combustion engine, the inlet tube 15 is connected to the exhaust pipe of the internal combustion engine and the exhaust gases enter at inlet opening 13, pass through tube 15 and emerge from the end of said tube where they expand into the relatively large area of the space within the chamber enclosed by casing 10, and reverse their direction and travel forwardly in said chamber to the open end of solid walled outlet tube 16, and thence through outlet tube 16 40 and outlet opening 14 and out of the silencer. The major proportion of the gases follows the path just described, while a minor proportion passes laterally through the perforations or openings of inlet tube 15 and follow a shorter path 45 forwardly to the open end of outlet tube 16. There is also an impingement of the gases against end walls 12 and 11 as they undergo reversal of direction at the ends of the silencer. The gases pass laterally through the openings of inlet tube 50

15 in quantities proportional to the pressure difference existing between the inside and the outside of the tubes. It is understood that in the exhaust of an internal combustion engine pulses at high pressure are followed by rarefactions at low pressure which may be lower than atmospheric pressure so that at such instant there may actually be a transfer of gas from the outside of the inlet tube to the inside. In other words, the transfer through the tube serves to relieve or attenuate both the high and low pressure conditions inside and outside of the tube and cause a general smoothing of the stream. The silencer is highly effective over the range which is important in internal combustion engine silencing, and it has been found that in many instances a smaller silencer may be used than is customary.

In Fig. 3 a modification of the invention is shown which is adapted for those applications in which concentric inlet and outlet silencer openings are desirable. In this modification the relative arrangement of the tubes is reversed, in that the inlet tube, instead of the outlet tube, is solid and the outlet tube is perforated. It has been found that the silencer is substantially equally effective with either arrangement. The silencer comprises imperforate casing 20 having inlet end wall 21 and outlet end wall 22, said end walls having inlet opening 23 and outlet opening 24 therein, in which are mounted the tube connections 25 and 26. A transverse partition 27 extends across the interior of casing 20 at a point adjacent and spaced inwardly from inlet end wall 21. In a similar manner, a second partition 28 extends across the casing at a point spaced inwardly from outlet end wall 22. Partitions 27 and 28 subdivide the casing into a silencing chamber 29 and two end chambers 31 and 32. Partitions 27 and 28 have openings 33 and 34 therein, said openings being displaced laterally with respect to each other and to the center line of the silencer. A solid, open-ended inlet tube 35 is mounted at one end in opening 33 of partition 27 and extends into silencing chamber 29 part way toward the opposite partition 28, and perforated, open-ended outlet tube 36 is mounted in a similar manner in opening 34 of partition 28 and extends into the chamber part way toward partition 27. Tubes 35 and 36 are arranged in juxtaposed relation and extend laterally adjacent each other throughout a large portion of their length within chamber 29.

When using this construction as an exhaust silencer, the exhaust gases enter tube connection 25 and pass into chamber 31 where they strike the central solid portion of partition 27 and then spread laterally and converge and pass into solid walled inlet tube 35, through this tube and thence through the interior space of chamber 29 to perforated tube 36, the action being similar to that described in connection with Figs. 1 and 2, except that there is a lateral flow of gases and sound through the walls of the outlet tube instead of the inlet tube. The gases emerging from outlet tube 36 impinge against the solid portion of the casing outlet wall 22 opposite the said tube 36, and then spread laterally and pass out of the silencer through outlet tube connection 26.

The modification illustrated in Fig. 4 is similar to that of Figs. 1 and 2 but has several additional sound attenuating chambers in which the attenuation is accomplished by means of resonators and porous sound-absorbing and gas-pres-

sure-absorbing material. It comprises an imperforate casing 40 having end walls 41 and 42 and intermediate partitions 43 and 44 subdividing the casing into direction-reversing chamber 45 and two additional chambers 46 and 47. End wall 41 has an inlet opening 48 therein, and outlet end wall 42 has an outlet opening 49 therein, and intermediate partitions 43 and 44 have openings 50 and 51 therein aligned with outlet opening 49. The inlet opening 48 and the outlet opening 49 are displaced laterally with respect to each other and to the center line of the silencer. Perforated inlet tube 53 is mounted in inlet opening 48 and extends into direction-reversing chamber 45 in the same manner as described heretofore in connection with Figs. 1, 2 and 3, and solid outlet tube 54 is mounted in the opening 50 of partition 43 and extends into the chamber 45, said outlet tube 54 continuing through chambers 46 and 47. The portion within chamber 46 has one or more openings 55 therein serving to connect the space within chamber 46 to the tube in sidebranch relation to form a resonator construction. The portion passing through chamber 47 is perforated, and this chamber is filled with porous sound-absorbing and gas-pressure-absorbing material 56 which exerts an attenuating effect upon the sound and gas pressure pulses passing through the tube 54 in the well-known manner.

In Figs. 5 and 6 a modification of the invention is illustrated in which there are two inlet tubes and two outlet tubes. The imperforate casing 60 has inlet end wall 61 and outlet end wall 62 to form a single silencing chamber. The perforated open-ended inlet tubes 63 are mounted in openings in the inlet end wall 61 and extend into the chamber to a point adjacent and spaced from outlet end wall 62, and in a similar manner solid outlet tubes 64 are mounted in openings in outlet end wall 62 and extend to a point adjacent and spaced from inlet end wall 61. The action of this silencer is similar to that of those described heretofore, this form being particularly adapted for the silencing of an internal combustion engine having two exhaust lines. It is understood that the silencer may have more than two inlet and outlet tubes, and that it may have any desired combination of inlet and outlet tubes, such as two inlet tubes and one outlet tube, or vice versa.

In the silencer of this invention it has been found that the area of the openings or perforations in the walls of the perforated tube or tubes may be varied within limits between approximately 0.03% and 10% of the total area of said walls. As has been stated heretofore, variation of the opening area within this range changes the performance characteristics of the silencer by varying the frequency response, and, therefore, the opening area may be varied to secure the best performance for the particular application.

While the action of the silencer has been described in connection with its use for the silencing of the exhausts of internal combustion engines, it is adapted as well for the silencing of intakes. There are some differences in the nature of the sounds and gas pulses which are encountered in the two applications. In exhaust silencing the sounds and pulses of gas at high temperature move in the same direction while in intake silencing the sounds move outwardly from the engine while the pulses of air at rel-

atively low temperature move inwardly. The silencer of this invention attenuates with equal effectiveness in both cases.

I claim:

- 5 1. A silencer comprising means forming a chamber, said chamber having inlet and outlet openings in opposite walls thereof, open-ended inlet and outlet conduits arranged in juxtaposed relation within said chamber, said inlet and outlet conduits being connected at one end thereof to said inlet and outlet openings, respectively, and each extending from the wall opening to which it is connected part way toward the opposite wall and having an open end located within 15 said chamber, said inlet and outlet conduits being arranged laterally adjacent one another throughout a portion of their length, the open ends of said conduits located within said chamber being in free and unconfined communication 20 with each other through the space within said chamber, the conduit extending from one wall of said chamber having imperforate walls, and the conduit extending from the other chamber wall having openings in the walls thereof.
- 25 2. A silencer comprising means forming a chamber, said chamber having at least one open-ended inlet tube mounted in one wall thereof and at least one open-ended outlet tube mounted in the opposite wall thereof, said inlet and outlet tubes being arranged in juxtaposed relation within said chamber and each extending from the wall in which it is mounted into said chamber part way toward the opposite wall, said inlet and outlet tubes being arranged laterally adjacent 30 one another throughout a portion of their length, the open end of said tubes located within said chamber being in free and unconfined communication with each other through the space within said chamber, the tube extending from one wall of said chamber having imperforate walls and the tube extending from the opposite wall of said chamber having perforated walls.
- 35 3. A silencer comprising means forming a chamber, said chamber having inlet and outlet openings in opposite walls thereof, open-ended inlet and outlet tubes mounted in said inlet and outlet openings respectively, said inlet and outlet tubes being arranged in juxtaposed relation within said chamber and each extending from the wall opening in which it is mounted into said chamber part way toward the opposite wall and ending in adjacent spaced relation to said opposite wall, said inlet and outlet tubes being arranged laterally adjacent one another throughout 40 45 50 55 60 a portion of their length, the open ends of said tubes located within said chamber being in free and unconfined communication with each other through the space within said chamber, the tube extending from one of said chamber walls having imperforate walls, and the tube extend-

ing from the opposite chamber wall having openings in the walls thereof.

4. The silencer of claim 1 in which the openings in the conduit having openings in the walls thereof occupy approximately 0.03% to 10% of 5 the total area of the walls of said conduits.

5. A silencer comprising a substantially imperforate casing having inlet and outlet openings therein, at least one transverse partition within said casing providing a chamber within 10 said casing, open-ended inlet and outlet tubes mounted in opposite walls of said chamber and communicating with said inlet and outlet openings respectively, said tubes being offset laterally with respect to each other and each extending 15 from the wall in which it is mounted into said chamber part way toward the opposite wall of said chamber and ending in adjacent spaced relation to said opposite wall, said oppositely extending tubes being arranged laterally adjacent 20 one another throughout a portion of their length and being directly exposed to one another, the open ends of said tubes located within said chamber being in free and unconfined communication with each other through the space within said 25 chamber, the tube extending from one wall of said chamber having imperforate walls and the tube extending from the opposite wall of said chamber having perforated walls.

6. The silencer of claim 5 in which at least 30 one chamber wall has a plurality of openings therein and a tube is mounted in each of said openings and extends toward but stops short of the opposite chamber wall.

7. A silencer comprising a substantially imperforate casing having inlet and outlet openings in opposite end walls thereof respectively, and having at least one transverse partition therein subdividing said casing into a plurality of chambers, one of said chambers having inlet and outlet openings in opposite walls thereof, open-ended inlet and outlet tubes arranged in juxtaposed relation within said chambers, said inlet and outlet tubes being connected at one end thereof to said inlet and outlet openings of said chamber respectively, and each extending inwardly from the wall opening to which it is connected part way toward the opposite wall of said chamber said inlet and outlet tubes being arranged laterally adjacent each other throughout a portion of 50 their length, the tube extending from one chamber wall having its walls imperforate, and the tube extending from the opposite chamber wall having openings in the walls thereof, and conduit means passing through the remainder of 55 the chambers in said casing and connecting said tubes with said casing openings, and sound attenuating means in said additional chambers in cooperative relation with said conduit means.

ROBERT L. HOYLE. 60
